BATTERY TERMINAL CONNECTION CLAMP

Carl R. Graves and John C. Stout, Clarion, Iowa

Application December 7, 1937, Serial No. 178,610

3 Claims. (Cl. 173—259)

This invention relates to battery terminal connectors, and more particularly, to an improved clamp for use with a battery cable to facilitate the engagement and removal of the cable from the terminal post of the battery.

An object of this invention is to provide an improved cable connector for a battery terminal post which is so constructed that it may be readily adjusted to different sizes of terminal posts, and which embodies means whereby the tightening bolt can be readily loosened so as to break up any corrosion which may form between the bolt and the clamping ears of the connector.

Another object of this invention is to provide a connector which may be used with battery cables, and which embodies means whereby the connector may be removed from the post by means of a screw driver or other tool so that the connector may be quickly removed from the terminal post of the battery in the event any corrosion occurs between the connector and the post.

A further object of this invention is to provide a connector of this type which is so constructed that in the event corrosion eats off a portion of the clamping device, the connector may still be used with the cable and the post so that the breaking of one portion of the connector clamping means will not make necessary the immediate replacement of the connector.

With the foregoing and other objects in view, the invention will be more fully described hereinafter, and will be more particularly pointed out in the claims appended hereto.

In the drawing, wherein like symbols refer to like or corresponding parts throughout the several views:—

Figure 1 is a top plan of a clamp constructed according to an embodiment of this invention.

Figure 2 is a detailed side elevation of the clamp.

Figure 3 is a sectional view taken on the line 3—3 of Figure 1 and showing the tightening yoke in released position with the bill of a screwdriver inserted therein to pry the clamp off of the terminal post.

Figure 4 is a sectional view taken on the line 4—4 of Figure 1.

Figure 5 is a fragmentary bottom plan of the clamp.

Referring to the drawing, the numeral 10 designates generally, a battery terminal clamp comprising a pair of integral clamping arms 11 and 12 having a socket 13 fixedly secured thereto. The configuration of the socket 13 may be varied to suit different conditions, but in the present

instance, this socket 13 is constructed in substantially U-shape so that the bared end of a cable 14 may be engaged in the socket 13, and the open sides of this socket 13 may be pressed together so as to tightly clamp the end of the cable 14 therein. In addition to this manner of holding the end of the cable 14, the cable may also be soldered or otherwise firmly secured in the socket 13.

The clamping member 11 is provided with an outstanding ear 15, and the clamping member 12 is provided with an ear 16 disposed in substantially parallel relation to the ear 15, and these ears 15 and 16 are adapted to receive there-through a tightening bolt 17.

A substantially U-shaped tightening yoke 18 is 15 adapted to have the parallel legs 19 and 20 pivotally mounted on the bolt 17 on the outer sides of the ears 15 and 16 respectively, and the leg member 19 is provided with an outstanding lug 21 adapted to engage against the head 23 of the 20 bolt 17 so as to hold bolt 17 against turning relative to the yoke 18.

The tightening nut 22 is threaded onto the opposite end of the bolt 17 and engages against the leg member 20 of the yoke 18. Preferably, the 25 clamping members 11 and 12 are provided with shoulders 24 and 25 respectively, against which the ends of the leg members 19 and 20 are adapted to engage when the yoke 18 is in clamping position so as to limit the swinging movement of the 30 yoke 18 beyond a substantially horizontal position or a position substantially aligning with the longitudinal axis of the connector.

The ear 16 is provided on the outer side thereof with a cam face 26 and the leg 20 of the yoke 18 35 is provided with a cam member or inwardly extending lug 27 engageable with the cam 26 so as to draw the two ears 15 and 16 toward each other when the yoke 18 is swung to a substantially horizontal operative or clamping position.

In the use and operation of this connector clamp, the cable 14 is fixed in the socket 13 and the clamping arms 11 and 12 are then slipped over the tapered top of the battery terminal post. Initially the yoke 18 is in substantially vertical released position, and when the clamping arms 11 and 12 are disposed about the terminal post, the yoke 18 is then swung downwardly to a substantially horizontal position thus forcing the ears 15 and 16 toward each other and tightening the 50 clamping members 11 and 12 about the terminal post.

In the event the substantially quarter turn of the yoke 18 is not sufficient to tightly clamp the clamping members 11 and 12 on the terminal 55

post, the nut 22 may be tightened with the yoke 18 in a released position. It will be apparent from this that the terminal clamp or connector may be used with either terminal of the battery, and the clamping members 11 and 12 may be initially adjusted so as to properly engage the post when in clamping position.

The movement of the yoke 18 from a released to a clamping position will, by reason of the lug 21, also effect turning of the bolt 17. This movement is also effected during the movement of the yoke 18 to a released position so that in the event the corrosion about the battery terminal post and the connector substantially freezes the bolt 17 in the ears 15 and 16, the movement of the yoke 18 will loosen the bolt 17 in the ears 15 and 16. When the yoke 18 is in a substantially vertical released position, a tool in the form of a screw driver or handle of a wrench may be inserted in the loop formed by this yoke 18 with one end of the tool resting on the top of the terminal post. The tool may then be used as a lever to forcibly pull the clamping arms 11 and 12 off of the terminal post.

25 This connector or clamp is adapted to be constructed of non-corrodible material so that it will not be eaten or otherwise affected by corrosion occurring about the terminal post due to the escape of gases about the terminal post.

30 It is, of course, understood that various changes and modifications may be made in the details of construction and design of the above specifically described embodiment of this invention without departing from the spirit thereof, such changes and modifications being restricted only by the scope of the following claims.

What we claim is:

1. A battery post clamp comprising a split clamping member, a cable socket carried by said member, a pair of spaced apart parallel ears carried by the free ends of said clamping member, a bolt engaging through said ears, a U-shaped

tightening member straddling said ears and mounted on said bolt to be oscillated relative to the ears, a cam on one of said ears, and a cam carried by said tightening member engageable with said first cam whereby to draw said ears toward each other upon rocking of said tightening member in one direction, and means securing the tightening member to the bolt to effect turning of the bolt with said means.

2. A battery post clamp comprising a split 10 clamping member, means for attaching a cable to said member, a pair of spaced apart ears carried by the free ends of said member, a headed bolt passing through and connecting said ears, a U-shaped tightening member having spaced apart 15 legs straddling said ears and having the bolt passing therethrough, coacting cam means carried by at least one of said ears and at least one leg of said U-shaped member to draw said ears toward each other upon rocking of said U-shaped 20 member in one direction, and means carried by the other leg of the U-member engaging the head of the bolt to effect turning of the bolt with the U-member.

3. A battery post clamp comprising a split 25 clamping member, means for attaching a cable to said member, a pair of spaced apart ears carried by the free ends of said member, a headed bolt engaging through said ears, a U-shaped tightening member having spaced apart legs 30 straddling the ears and through which the bolt passes, coacting cam means carried by at least one of said ears and at least one leg of said U-shaped members to draw said ears toward each other upon rocking of said U-shaped member in 35 one direction, and a lug carried by said U-shaped member engaging the head of said bolt to effect turning of the bolt with said U-shaped member, to break away corrosion from between the bolt and ears.
